JOHN SEIXAS MACGLASHAN, OF CINCINNATI, OHIO, ASSIGNOR OF ONE-HALF TO
GEORGE B. MAGGINI, OF CINCINNATI, OHIO.

MEANS FOR HOLDING AND SUSPENDING BALLS OF THREAD, &c.

1,189,275.

Specification of Letters Patent.

Patented July 4, 1916.

Application filed January 20, 1915. Serial No. 3,356.

To all whom it may concern:

Be it known that I, JOHN SEIXAS MACGLASHAN, a citizen of the United States, residing at Cincinnati, in the county of

5 Hamilton and State of Ohio, have invented new and useful Improvements in Means for Holding and Suspending Balls of Thread, &c., of which the following is a specification.

10 My invention relates to means for holding and suspending balls of yarn, thread, twine, etc.

The object of my invention is to afford a means not only for holding said balls, but 15 also for suspending the same from any suitable and convenient point of the clothing of a person while crocheting, knitting, etc., in order to prevent the dropping of said balls or the tangling of the thread, yarn, etc., 20 which under the present method of holding said balls so frequently happens. I accomplish this object by means of the mechanism set forth and described in this specification and illustrated by means of the accompanying drawing, in which like reference characters represent like parts in all figures.

Figure 1 is an elevation of my new and improved holder. Fig. 2 is an elevation of my new and improved holder in connection 30 with a suspending chain and bar-pin. Fig. 3 is an elevation of my new and improved holder not only in connection with a suspending chain and bar-pin, but also in combination with a ball of thread mounted on 35 said holder and clamped and firmly held thereby. In this figure, the bar-pin is turned slightly out of its normal position in order to show to better advantage the chain connection therewith.

40 In all figures A is the holder.

B is the chain.

C is a safety bar-pin.

1 is the swivel of the chain.

2 is the eye of the holder.

45 3 are lateral resilient turns in the holder arms.

4 are the corrugations near the end of the holder arms.

5 are the barbs on the end of the holder 50 arms.

6 is the ball of thread. It is to be understood here that the word thread means any suitable material employed in crocheting, knitting, sewing and the like.

55 7 is the pin of the bar-pin.

8 is the clasp that engages the point portion of said pin and not only protects the point of said pin, but also secures said pin in holding position.

Having thus described my invention in 60 detail and by illustrations, I will now describe it as a working mechanism.

In mounting the ball on the holder, the thumb is placed in one of the lateral turns 65 3 and one of the other fingers in the other turn. The ball is held in the other hand. The two arms of the holder are then brought together by the action of said fingers, and the ball is then mounted on these arms, or, in other words, these arms are then thrust 70 into the central cavity or opening in the ball. The pressure of the fingers being then removed from said arms, said corrugations and said barbs of said arms are, by the elasticity of the material out of which said 75 holder is made, brought hard against the diametrically opposite sides of said internal cavity of said ball with the effect and result that the barbs engage and penetrate the ball and the outer turns of said corrugations 80 press hard against the sides of said internal cavity and in that way give firmness and steadiness to said holder so that it does not wriggle from side to side of said internal cavity when in operation. The ball having 85 thus been mounted on said arms, said bar-pin is secured to such point on the clothing of the person using said holder and ball as appears to be the most convenient therefor. The end of the thread then having been 90 found, the thread is unwound by simply pulling on it, the ball turning around in the manner of a top, the said swivel in said chain affording the means for it doing so. It is in this manner that the work of knitting or crocheting is carried on without the least fear of dropping the ball or of tangling the thread. If the person using said 95 holder and ball desires to move from one place to another, this can be done without 100 any care whatever as to said ball, and this is an exceeding great convenience.

Thus it is seen that in the use of my improved holder, the users thereof can change their position while using the same without 105 any danger of loosing the ball or tangling the thread, and this again is another very great convenience. To lay the ball aside, it is only necessary to unpin the bar-pin from the clothing, in which event the ball re- 110

mains mounted on the holder and ready to be again attached to the clothing for use as aforesaid.

Having thus described my invention in detail, by illustrations and as a working mechanism, what I claim is:—

- In means for holding and suspending balls of thread, a holder having a spring-looped eye therein and arms diverging first therefrom and then striking a course parallel with each other, said arms at the point of the beginning of said parallel course having in each a loop or turn and then next thereafter corrugations and next thereafter out-
- 10

turned barbs, said loops at the beginning of 15 said parallel course being adapted to receive the ends of the fingers, to give resiliency to said arms and to form a sort of back-stop for a ball of thread mounted thereon.

20 In testimony whereof I have hereunto set my hand in presence of two subscribing witnesses.

JOHN SEIXAS MACGLASHAN.

Witnesses:

ALBERT S. NOVELL,

WILLIAM JOHN SCHULTZ.
